KEY AND COMBINATION OPERATED LOCK

Harold Machinist, Chicago, Ill., assignor to Dudley Lock Corporation, Chicago, Ill., a corporation of Illinois

Application February 28, 1940, Serial No. 321,173

13 Claims. (Cl. 70—319)

This invention is concerned with locks of the type which include a permutation mechanism through which the bolt or locking member is operable, and also a key-operated mechanism for independently actuating such locking member. One object of the invention is to provide a simple and reliable mechanism of sturdy construction and designed for economical production. Another object is to provide a normally disengaged coupler between the key-operated mechanism and the bolt-actuating means, adapted to be automatically engaged upon insertion of the proper key. A further object is to include in the structure means controlled by the key-operated mechanism and adjustable for altering the position of the dial relative to the permutation mechanism for changing the operating combination at will. The invention consists of certain features and elements in combination, as herein shown and described and as indicated by the claims.

In the drawings:

Fig. 1 is a face view showing a cabinet lock of the type embodying this invention as mounted on a cabinet door or other closure member.

Fig. 2 is a vertical section taken substantially at the axis of the knob on Fig. 1.

Fig. 3 is taken as a section as indicated at line 3—3 on Fig. 2 and shows the relation of the permutation disks to the bolt.

Fig. 4 is a section taken principally as indicated at line 4—4 on Fig. 2 for showing the bolt-actuating means which is operable by the key-controlled mechanism.

Fig. 5 is a horizontal axial section taken as indicated at line 5—5 on Fig. 2.

Fig. 6 is a transverse detail section as indicated at line 6—6 on Fig. 5.

Fig. 7 is a transverse section at line 6—6 on Fig. 5, showing the plug turned through the limited angle in which it actuates the clutch for key operation of the lock.

Fig. 8 is a transverse detail section at the line 8—8 on Fig. 5, but with the key plug and casing in elevation and showing the parts in the same position as in Fig. 7.

Fig. 9 is a transverse detail section at the line 9—9 on Fig. 5, but with the key plug and casing in elevation.

Fig. 10 is a transverse section at the line 9—9 on Fig. 5, but with the key plug and casing in elevation and showing the plug turned to the angle for declutching the knob in the resetting operation.

Fig. 11 is a transverse detail section at the line

11—11, on Fig. 5, but with the key plug and casing in elevation and showing the parts in the same position as in Fig. 10.

The lock which is the subject of this invention is adapted for various types of closures, such as lockers, wall safes, cupboards or cabinet drawers. As illustrated, the lock mechanism is contained in a case 1 of rectangular outline, having flanges 2, 2 at opposite ends for securing against the rear face of a door or other closure such as that indicated as a thickness of sheet metal at 3 in Fig. 1. A face plate 4 is applied to the outer face of the door panel 3 and has a rotatable knob 5 and a dial 6 associated with it. The knob is provided with a key slot 7 for the introduction of a key to actuate the bolt 8 independently of the permutation mechanism, and this same key slot may receive a second key for use in changing the combination of the permutation mechanism. The bolt 8 is slidably carried in the case by a plate 9 which may be integral with the bolt, or may comprise a portion of it, and which is guided between the end walls 10, 10 of the case for movement sufficient to project the bolt 25 through a suitable opening in the wall 11 or withdraw it to a position substantially flush with that wall. Within the casing 1 and spaced from the back wall 12 a partition plate 13 provides a surface upon which the plate 9 is slidably carried, and extending forwardly from the partition 13 a bearing sleeve 14 serves to journal the spindle 50 which operates the bolt through a key mechanism, as hereinafter described; and the sleeve 14 also serves as a bearing for the tumbler disks 15, 16 and 17 of the permutation mechanism. These disks are separated by the usual spacing washers 18 and are interengageable with each other by means of lugs 19 which project from adjacent faces of the tumbler disks. The outer disk 17 is formed with a hub 20 having notches 21 which interengage with lugs 22 of a drive member 23 whose function is to transmit rotation from the knob 5 to the permutation disks in a manner about to be described.

Within the knob 5 there is mounted the cylindrical casing 30 and the key plug 31 of a key-controlled cylinder lock. The interior surface of the knob 5 is formed with a plurality of angularly spaced pockets 32 and a hole 33 in the casing 30 carries a clutch ball 34 normally in engagement with one of the pockets 32. The cylindrical surface of the key plug 31 supports the ball 34 in this relation, the diameter of the ball being greater than the thickness of the wall of the casing 30 as seen in Fig. 5. Near its inner end the cas-

ing 38 is provided with a pair of radially projecting lugs 35 which engage in notches 36 in the annular rim of the drive member 23. Thus, with the casing 30 connected to the knob 5 by the lugs 35 the rotation of the knob 5 is transmitted to the tumbler disk 17 and movement is communicated from that disk to the tumblers 16 and 15 by way of their lugs 19 in setting up the proper arrangement of the permutation disks for actuation of the bolt 8. This portion of the mechanism and its operation is more fully described in my pending application Serial No. 278,641, filed June 12, 1939.

The plate 9 which is rigidly associated with the bolt 8 carries a pawl 25 connected to the plate by a pivot 26 and urged by a spring 27 into contact with the peripheries of the disk tumblers 15, 16 and 17 as seen in Fig. 3. These tumblers are notched as at 28 to receive the nose of the pawl 25 when the tumblers are adjusted in their bolt-releasing position, but, except when thus adjusted, the tumblers hold the pawl in engagement with a stop lug 44 upstanding in the casing 1 from a plate 43 which is slidably mounted adjacent the back wall 12 of the casing. The plate 40 is separated from the tumbler disks in the casing by the partition 13 and is mounted for sliding between the end walls 10, 10 so as to be movable in the same direction as the bolt 8 and its attached plate 9. The spindle 50 carries an arm 42 which bears against the edge 43 of the cam-shaped opening in the plate 40 and this opening is so formed that rotation of the spindle 50 and its arm 42 operates to slide the plate 40 within the casing. This sliding movement in one direction is transmitted by stop lug 44 and pawl 25 to the bolt plate 9 for projecting the bolt 8 to the position shown in Fig. 4, and return movement of the plate 40 causes the upstanding stop 44 to engage a shoulder 45 which is the end of a slot 46 in the plate 9 for withdrawing the bolt.

The forward end of the spindle 50 is flattened at 51 to fit into the flat-sided opening 52 in the driving stud 53; and a cup-shaped head 54 on the stud fits over a reduced annular part 37 of the cylindrical lock casing 30. The part 37 is formed with a slot or aperture 38 which carries a clutch ball 55 and the key plug 31 has a reduced terminal portion 39 fitting rotatably within the annular part 37 of the casing, and providing a recess or pocket 56 in which the ball 55 normally rests. The inner surface of the cup-shaped head 54 is formed with a continuous series of pockets 57 similar to the pocket 56 and the thickness of the annular part 37 of the casing is less than the diameter of the ball 55. Thus the relative rotation of the plug terminal 39 through a few degrees within the head 54 of the driving stud 53 serves to cam the ball 55 out of the pocket 54 until the cylindrical surface of the plug terminal 39 supports the ball in engagement with one of the pockets 57 so that it constitutes a driving connection between the reduced portion 37 of the casing 30 and the stud 53. As already noted, the stud 53 is interconnected with the spindle 51 for rotating the latter and its attached arm 42 in the key operation of the bolt.

The key plug 31 is provided with pin tumblers or equivalent elements such as those seen at 60 in Fig. 2, and these tumblers normally interengage with grooves 61 in the casing 30. Insertion of a proper key in the key slot 7 serves to withdraw the tumblers 60 into the plug and out of engagement with the grooves 61 to permit

rotation of the plug within the casing, but this key leaves one tumbler 62 still projecting. A portion of the casing 30 is cut away at 63 to form an arcuate slot of limited angular extent, terminated by shoulders 64 and 65 so that the relative rotation of the plug 31 within the casing 30 is thus limited, and further rotation of the plug by means of its key will carry with it the casing 30 after the limited rotation has served to project the ball 55 into engagement with one of the pockets 57 of the driving stud 53. Such further rotation of the key—say, in clockwise direction, with the tumbler 62 engaging the shoulder 65—will turn the casing 30 and with it the spindle 50 and its arm 42 for moving the plate 40 in the direction to withdraw the bolt 8 which is shown projected in Fig. 4. Reverse rotation of the key and plug 31 will first carry the projected tumbler 62 away from the shoulder 65 without turning the casing 30 or shifting the bolt, and as the plug 31 turns within the casing 30 the pocket 56 will momentarily receive the ball 55. But since the arcuate slot 63 extends equally in both directions from the position of the tumbler 62 when the plug is locked in the casing 30 it will permit further rotation of the plug in counter-clockwise direction, forcing the ball 55 into one of the pockets 57 and continuing until the tumbler 62 encounters the shoulder 64 whereupon the casing 30 itself will be turned in counter-clockwise direction, and will transmit such rotation to the spindle 50 and arm 42 carrying said arm and the cam plate 40 to the position indicated in full lines in Fig. 4, and projecting the bolt 8.

But to permit withdrawal of the key, as is usual in locks of this type, it must be swung back to mid-position at which the tumblers 60 register with the proper grooves 61 of the casing 30 so that when the key is withdrawn the tumblers will be released for projection into these grooves 61 and the plug 31 will be locked against rotation in the position at which the recess or pocket 56 receives the clutch ball 55. Thus the inner end portion 37 of the lock casing 30 is normally disconnected from the head 54 of the driving stud 53 so that the knob 5 which is normally connected to the casing 31 can be rotated freely without actuating the spindle 50 and its arm 42.

With the knob 5 positively engaged with the tumblers 17 in a definite relation thereto, the permutation tumblers are adjusted by shifting the knob to certain successive dial readings secured by registering the proper scale points of its dial 6 with the fixed index mark 66. This series of adjustments will serve as long as the clutch ball 34 remains in the same pocket 32 of the knob. But the key plug 31 is formed with a recess 67 circumferentially aligned with the clutch ball 34 but normally spaced 90 degrees away from it, when the plug is in locked position in its casing 30. By means of a special key the locking tumblers 60 and also the special tumbler 62 may be withdrawn into the plug so as to permit relative rotation of the plug 31 within the casing 30 through more than the angle permitted by the arcuate slot 63 and far enough to bring the recess 67 into registration with the ball 34. Slight rotation of the knob 5 relative to the casing 30 will then cam the ball 34 out of the pocket 32 which it occupies, and since the recess 67 is deep enough to hold the ball entirely clear of the inner surface of the knob 5 the latter may be turned freely through any desired angle, and will thus be shifted into a dif-

ferent relation to the casing 30 and to the tumbler 17 which is interlocked with the casing through the driving member 23. The knob may then be reconnected to the casing 30 by engagement of the ball 34 in any other pocket 32 and by returning the plug 31 back to its normal locked position, thus camming the ball out of the recess 67 and forcing it back into driving relation with the knob 5 at the new adjustment of the latter. If desired, a second arcuate slot 68 may be formed in the casing to register with another special tumbler 69 which will be left projected by the special key which is used for resetting the knob 5 as just described; and the slot 68 as shown in Fig. 11, will permit only the exact 90 degrees of rotation of plug 31 in the casing 30 required to bring the recess 67 into registration with the ball 34.

I claim:

1. In a lock which includes a bolt and combination mechanism adjustable for operating the bolt, independent operating means for the bolt including a key-controlled cylinder lock comprising a key plug and a casing, said casing being constantly connected with the combination mechanism, a knob and clutch means normally connecting the knob with the casing, said key plug being formed to release the clutch when rotated through a limited angle by a reset key to permit resetting the knob in relation to said mechanism for changing the operating combination.

2. In a combination lock, a key controlled lock comprising a key plug and a cylindrical casing for the plug connected with the combination mechanism, a knob rotatably adjustable on the casing, clutch means movably carried by the casing and by which the knob is engageable with the casing at a plurality of positions of rotative adjustment, key operable cam means normally holding the clutch means in position to connect said knob with the casing, and movable by rotation of the plug by a proper key to a position in which said cam means releases said clutch means to permit rotative adjustment of the knob on the casing for changing its relation to the combination mechanism and thus altering the operating combination.

3. In a combination lock, a cylindrical casing connected with the combination mechanism, a knob rotatably adjustable on the casing and formed with a plurality of recesses open toward said casing, a clutch element carried by the casing and normally engaged with one of said recesses for connecting the knob with the casing, and key operable means rotatable in the casing, the rotation of said means in the casing acting to release said clutch means to permit rotative adjustment of the knob into a different relation with the combination mechanism for thus altering the operating combination.

4. In a combination lock, a cylindrical casing connected with the combination mechanism, a knob rotatably adjustable on the casing, said casing having an aperture with a clutch member carried therein, and a key plug rotatably mounted in the casing, said knob having a plurality of recesses open toward the casing and positioned to register with said aperture, the key plug normally supporting the clutch member in position to project into one of said recesses for locking the knob and casing together, said plug having a pocket registerable with the clutch member by rotative adjustment of said plug under control of a reset key to permit disengagement of the knob

from the casing and rotative adjustment of the knob for changing its relation to the combination mechanism and thus altering the operating combination.

5. In a lock mechanism which includes a bolt and combination mechanism adjustable for operating the bolt, independent operating means for the bolt including a key-controlled cylinder lock comprising a key plug and a casing, said casing being constantly connected with the combination mechanism, a knob and clutch means normally connecting the knob with the casing, said key plug being operable by a reset key to disengage the clutch to permit resetting the knob in relation to said mechanism for changing the operating combination, said plug including a tumbler which is left projecting when the plug is operated by said reset key, and the casing having an abutment shoulder positioned for encounter by the tumbler to limit rotation of the plug to the amount required for releasing the clutch.

6. In a lock which includes a bolt and combination mechanism adjustable for operating the bolt, independent operating means for the bolt including a key-controlled cylinder lock comprising a key plug and a casing, said casing being constantly connected with the combination mechanism, means for connecting said key plug with said independent operating means but normally disengaged therefrom, a knob and clutch means normally connecting the knob with the casing, said key plug being rotatable by a reset key to disengage the clutch to permit resetting the knob in relation to said mechanism, said plug including a tumbler which is left projecting when the plug is operated by said reset key and the casing having means to cooperate with said tumbler to limit rotation of the plug at the position for releasing the clutch.

7. In a lock which includes a bolt and combination mechanism adjustable for operating the bolt, independent operating means for the bolt including a key-controlled cylinder lock comprising a key plug and a casing, the casing having an aperture with a clutch element loosely carried therein, the plug having a recess normally registered with said aperture in the locked position of the plug with a cylindrical surface adjacent said recess, and the independent bolt-operating means including an annular member having inwardly facing pockets positioned to register with the aperture of the casing whereby rotation of the plug in its casing by means of a proper key serves to force the clutch element outwardly into one of said pockets to interlock the casing with said annular member, and means for turning said casing to operate the bolt.

8. In a lock which includes a bolt and combination mechanism adjustable for operating the bolt, independent operating means for the bolt including a key-controlled cylinder lock comprising a key plug and a casing, the casing having an aperture with a clutch element loosely carried therein, the plug having a recess normally registered with said aperture in the locked position of the plug with a cylindrical surface adjacent said recess, and the independent bolt-operating means including an annular member having inwardly facing pockets positioned to register with the aperture of the casing whereby rotation of the plug in its casing by means of a proper key serves to force the clutch element outwardly into one of said pockets to interlock the

casing with said annular member, the plug including a tumbler which is left projecting when the plug is operated by said key, and the casing having means positioned to engage said tumbler after limited rotation of the plug sufficient to actuate the clutch element whereby further rotation of the plug operates the bolt.

9. In a lock which includes a bolt and combination mechanism adjustable for operating the bolt, independent operating means for the bolt including a key-controlled cylinder lock comprising a key plug and a casing, the casing having an aperture with a clutch element loosely carried therein, the plug having a recess normally registered with the said aperture in the locked position of the plug with a cylindrical surface adjacent said recess, and the independent bolt-operating means including an annular member having inwardly facing pockets positioned to register with the aperture of the casing whereby rotation of the plug in its casing by means of a proper key serves to force the clutch element outwardly into one of said pockets to interlock the casing with said annular member, the plug including a tumbler which is left projecting when the plug is operated by said proper key, and the casing having a clearance groove for said tumbler terminating in an abutment shoulder positioned for encounter by the tumbler to limit the rotation of the plug within the casing for actuating the clutch element, such encounter providing a driving engagement by which further rotation of the plug operates the bolt.

10. In a lock, a bolt and operating means therefor including a key plug and a casing, said casing having an aperture with a clutch element loosely carried therein, the plug having a recess normally registered with said aperture in the locked position of the plug and having a cylindrical surface adjacent said recess, said operating means for the bolt including also an annular member having inwardly facing pockets positioned to register with the aperture of the casing whereby rotation of the plug in its casing by means of a proper key serves to force the clutch element outwardly for interlocking the casing with the annular member, together with means for interlocking the plug with the casing upon further rotation of the plug whereby continued rotation of the plug serves to actuate the bolt-operating means.

11. In a lock which includes a bolt, combination mechanism adjustable for operating said bolt, independent means for operating said bolt, a key-controlled cylinder lock for actuating said independent means and a rotatable knob for adjusting the combination mechanism, said cylinder lock comprising a key plug and a casing, said knob being rotatably mounted on the casing, clutch means normally connecting the knob

to the casing, and a second clutch means for connecting said casing with said independent bolt-operating means but normally disengaged therefrom, a coupling member constantly connecting the casing with the combination mechanism, said key plug being rotatable relatively to the casing through a limited angle in the actuation of the independent bolt-operating means, detent means limiting said angle but releasable by a key other than that which operates the bolt whereby the plug is permitted a greater angle of relative rotation for disengagement of the knob from the casing to allow resetting the knob in a different relation to the combination mechanism.

12. In a combination lock, a cylindrical casing connected with the combination mechanism, a knob rotatably adjustable on the casing, said casing having an aperture with a ball loosely carried therein, the diameter of the ball being greater than the thickness of the casing, and a key plug rotatably mounted in the casing, said knob having a plurality of recesses open toward the casing and spaced at intervals to register successively with said aperture, the key plug normally supporting said ball in the aperture in position to project into one of said recesses as a clutch member locking the knob and casing together, said plug having a depression deep enough to accommodate the portion of said ball by which it exceeds the thickness of the casing, said depression being registerable with the ball by rotative adjustment of the plug under control of a reset key to permit rotative adjustment of the knob relative to the casing for changing its relation to the combination mechanism and thus altering the operating combination.

13. In a lock which includes a bolt and combination mechanism adjustable for operating the bolt, independent operating means for the bolt including a key-controlled cylinder lock comprising a key plug and a casing, said casing having an aperture with a ball loosely carried therein, the diameter of the ball being greater than the thickness of the casing, the plug having a recess normally registered with said aperture in the locked position of the plug and deep enough to accommodate the portion of said ball by which it exceeds the thickness of the casing, said plug having a cylindrical surface adjacent the said recess, and the independent bolt-operating means including an annular member having inwardly facing pockets positioned to register with the aperture of the casing whereby rotation of the plug in its casing by means of a proper key serves to force the ball outwardly into one of said pockets to interlock the casing with said annular member, and means for turning said casing to operate the bolt.

HAROLD MACHINIST.
